Specification for Design.

Patented Mar. 23, 1920.

Application filed October 15, 1917. Serial No. 196,763. Term of patent 3½ years.

To all whom it may concern:

Be it known that I, BREWSTER P. KINNEY, a citizen of the United States, residing at East Cleveland, in the county of Cuyahoga and State of Ohio, have invented a new, original, and ornamental Design for a Holder for Knitting or Crochet Needles, of which the following is a specification, reference being had to the accompanying drawings, forming part thereof.

In the drawings, Figure 1 is a front view, Fig. 2 is a side view, and Fig. 3 is a perspective view of a holder showing my new design.

I claim:

The ornamental design for a holder for knitting or crochet needles, as shown.

BREWSTER P. KINNEY.
